VERTEBRÆ ADJUSTER

Filed Sept. 20, 1928

FIG. 2.

Inventor
William R. Hamilton
By Kenner E. Hedges
his attorney

UNITED STATES PATENT OFFICE

WILLIAM R. HAMILTON, OF DEWEY, OKLAHOMA

VERTEBRÆ ADJUSTER

Application filed September 20, 1928. Serial No. 307,302.

This invention relates to an improvement in vertebræ adjusters.

It is a well known fact that the vertebræ in the human spine often become dislocated, and since the nervous system and nervous column are centered in the spinal column, the nerves entering the latter through small holes or openings between the vertebræ, and when the vertebræ become thus dislocated, they bear against the nerves, which causes inflammation and pain in the different parts of the body to which the nerves lead, which will continue until the vertebræ are put back into their proper places.

Heretofore, this has been done by chiropractic treatments. The doctor places his fingers upon opposite sides of the spinal column at intervals along its length and by pressing on the vertebræ, any that may be dislocated are pushed back into their proper positions.

The object of this invention is to accomplish this treatment at home and without the necessity of treatment being given by a chiropractor.

The invention is adapted to allow the patient to receive the treatment by his own efforts and, being of a simple nature, is likewise relatively inexpensive and may be adjusted according to the height of the person using the same and also to properly correspond with the position of the patient's spine.

In the accompanying drawings:

Fig. 1 is a perspective view of the invention as applied;

Fig. 2 is a plan view of the invention partly in section; and

Fig. 3 is a detached perspective view of the adjuster.

The invention may be constructed of any kind of metal but in order to simplify its construction it is preferably made of some sheet metal and, as shown in Figs. 2 and 3, the sheet material is bent into an approximately V-shape body portion 1, which may be of a desired length of approximately eighteen inches. The apex 2 is smooth and properly rounded off to engage the back of the patient on opposite sides of the spinal column, as shown in Fig. 2. The sides of

the body portion 1 terminate in approximately L-shaped flanges 3, which are adapted to embrace the opposite edges of a suitable support 4, as for instance a door frame or casing, as shown in Fig. 1, where they are clamped by means of the bolts 5 which extend through the slots 6 in the opposite sides of the body portion 1, these bolts being provided with wing nuts 7 for tightening the adjuster on the support or casing.

In using the adjuster, it is regulated to the proper height on its support, which, as stated above, may be a door frame or casing, and is clamped in such position by the bolts 5. The patient may thus press his back against the edge 2 of the adjuster so that said edge engages on either side of the spinal column, and by exerting pressure against the edge 2 it may be determined at what point there is any pain, which may indicate that any of the vertebræ are out of their proper and normal positions.

By exerting a greater pressure on the edge of the adjuster at such points, the vertebræ may be snapped back into their proper positions to relieve the pain and also the pressure on the nerves entering the spinal column at such point. The adjusting of the invention on a door casing or frame allows the patient to press himself against the opposite side thereof for exerting proper and required pressure against the vertebræ, in order to accomplish the desired adjustment.

The invention is extremely simple and enables the patient to easily adjust it in proper position for giving himself a chiropractic treatment or adjustment, and in this way allows for the self administration of chiropractic treatments whenever pains may exist at different parts of the body and for the relief thereof.

I claim:

1. As a new article of manufacture, a vertebræ adjuster formed of a strip of material bent into approximately V-shape with an elongated apex for engaging the vertebræ of the human spine, flanges formed at the sides of said adjuster for engaging a support, and adjustable means connected with the adjuster

for adjustably clamping the flanges in their supported position.

2. A vertebræ adjuster comprising a strip of material approximately V-shape in form with an elongated apex for engaging the vertebræ of the human spine, and means for holding said adjuster in proper position.

3. A vertebræ adjuster comprising a strip of material approximately V-shape in form with an elongated edge for engaging the vertebræ of the human spine, the sides of said V-shaped portion forming clamping means, and adjusting means therefor.

4. A vertebræ adjuster comprising a strip of material provided with an elongated edge for engaging the vertebræ of the human spine, the sides thereof having clamping means connected therewith.

5. A vertebræ adjuster comprising a strip of material bent to form an elongated edge for engaging the vertebræ of the human spine, the sides thereof terminating in clamping flanges, and means for adjustably clamping the flanges in a supported position.

25 In testimony whereof I affix my signature.

WILLIAM R. HAMILTON.
